UNITED STATES PATENT OFFICE.

PASQUINO FERRARI, OF FALL RIVER, MASSACHUSETTS.

COVER FOR MILK-BOTTLES.

1,156,989.

Specification of Letters Patent. Patented Oct. 19, 1915.

Application filed May 26, 1914. Serial No. 841,052.

To all whom it may concern:

Be it known that I, PASQUINO FERRARI, citizen of the United States, residing at Fall River, in the county of Bristol and 5 State of Massachusetts, have invented certain new and useful Improvements in Covers for Milk-Bottles, of which the following is a specification.

My invention relates to new and useful 10 improvements in closure caps for different types of liquid containers and has particular reference to those which are employed in sealing milk bottles.

The principal object of my invention is 15 to provide for a milk bottle a closure which consists essentially in a body disk of cardboard or similar material and an apron which is secured thereto and is formed from relatively stiff and heavy paper.

20 A further object is to so crimp that portion of the apron which is adjacent the edge of the body disk that an inwardly extending lip or flange is formed over the upper face of the disk and in spaced relation 25 thereto so that any dealer using the closure may readily insert an ordinary cap bearing his own trade-mark or insignia by merely engaging such a cap under the flange or lip.

30 A still further object and one of equal importance with the foregoing is to crimp the peripheral portion of the apron to produce an annular rim which depends from the body disk and is adapted to engage against 35 the customary bead upon the upper edge of the bottle neck for the purpose of holding the closure against displacement.

Another and more general object is to 40 provide a closure which embodies in its construction the necessary features of simplicity, durability, efficiency and cheapness of production.

The above recited and other incidental 45 objects of a similar nature, which will be hereinafter more specifically treated, are accomplished by such means as are illustrated in the accompanying drawings, described in the following specification and then more particularly pointed out in the claims which 50 are appended hereto and form a part of this application.

With reference to the drawings, wherein there has been illustrated the preferred embodiment of this invention as it is reduced

to practice and throughout the several views, 55 of which similar reference characters designate corresponding parts,

Figure 1 is a perspective view of the neck of a milk bottle with the closure in position thereon; Fig. 2 is a view of the 60 blank from which the skirt of the closure is formed; Fig. 3 is a plan view, showing the body disk of the closure in position on the skirt; Fig. 4 is a section taken diametrically 65 through the closure and illustrating the first step in the shaping of the skirt; Fig. 5 is a section taken diametrically through the closure after the skirt has been completely shaped.

As illustrated in Fig. 1 particularly of 70 the accompanying drawing, my invention consists essentially in a circular body disk 10 and an apron or skirt 11 which is formed preferably of relatively heavy and comparatively stiff paper, such as is commercially 75 known as wrapping paper.

The body disk 10 is, in its preferred form, fashioned from relatively thick cardboard of the oil impregnated type such as is ordinarily used in making the well known 80 milk bottle cap. While it may be found, in some instances, desirable to imprint the name of a dealer on the body disk so that it is not necessary to apply a separate disk bearing the dealer's trade-mark or other 85 insignia, it has been found more practical, when manufacturing the closures in large quantities, to make the body disks of plain cardboard since by following this procedure a large quantity of the closures may be 90 made and distributed to any desired number of different dealers.

The skirt or apron 11 is, as best shown in detail in Fig. 2, formed from a single sheet of heavy, stiff paper, which is first cut to 95 circular form and is then notched or scalloped on its periphery to simulate the outline of an ordinary ratchet disk. The purpose in thus forming the periphery of the skirt blank will be hereinafter more fully 100 disclosed in that portion of the specification which will be devoted to a description of the application of the skirt to the bottle neck. During the manufacture of the bottle closure, the disk 10 is secured to the center of the skirt 11 by a film of glue or other adhesive. In this connection, it will of 105 course be obvious that if so desired a me-

talic fastening clip of any type may be employed instead of an adhesive. After the disk has been properly attached to the apron, the portion of this latter member 5 which is adjacent the edge of the disk, is crimped, as illustrated particularly in the sectional view of Fig. 5, to form the inwardly extending lip or flange 12, which is spaced from the upper face of the disk and 10 extends inwardly beyond the limits of the edge thereof. The material of the apron is next creased at the extreme inner edge of the lip 12 and is directed outwardly and downwardly, producing the depending rim, indicated in Fig. 5 by the numeral 13. This 15 rim is, as stated, annular in shape and is formed by creasing the outer edge portion of the skirt along a number of fold lines as illustrated particularly in the blank view 20 of Fig. 3. It will be noted upon reference to this figure that there extends inwardly from the apex of each tooth-like projection or notch 14 of the blank a dotted line, and that immediately adjacent each one of these 25 dotted lines there is a second dotted line which extends from the inner end of the adjacent notch. These two dotted lines, which extend from each tooth and adjacent notch, intersect at a point lying within a circle 15, 30 which represents, in Fig. 3, the inner edge of the disk 10.

It is now to be noted by reference to Fig. 5 particularly that the triangular fields 16, which are comprehended between the various 35 pairs of fold lines, are arranged, when the member 13 has been completely shaped, between the overlapping terminals of those portions of the skirt which are included between the several notches and teeth.

40 Inasmuch as the fields between the various pairs of fold lines are triangular and are arranged with their base portion outermost, it is apparent that the lower edge of the rim 13 will be of a diameter less than the diameter 45 of the upper portion of the rim and that for this reason, the lower edge of the rim, when applied to the milk bottle, will engage beneath the lower edge of the annular

rib or flange such as is customarily provided for all standard milk bottles.

50

In concluding the description of my invention, it remains only to explain that when the closure, illustrated in Fig. 1, has been applied to the bottle, the dealer may readily insert his own cap beneath the inwardly extending lip 12 in the same manner as he would apply it to a milk bottle unaccompanied by my closure.

55

In reduction to practice, it has been found that the form of this invention illustrated in the drawing, and referred to in the above description as the preferred embodiment, is the most efficient and practical; yet realizing that the conditions concurrent with the adoption of this device will necessarily vary, 60 it is desired to emphasize the fact that various minor changes in details of construction, proportion and arrangement of parts may be resorted to, when required, without sacrificing any of the advantages of this invention, as defined in the appended claim.

65

Having thus described the invention, what is claimed as new is:

A bottle closure including a circular skirt, a circular body disk secured to the center 75 of the skirt, the said skirt being crimped adjacent the periphery of the disk to provide an annular lip, laterally spaced upon one side of the disk and extending inwardly thereover, the said lip being adapted to engage over the periphery of a second disk adapted to seat upon said first mentioned disk, the outer margin of the skirt being folded along pairs of diagonally extending fold lines to produce a depending rim consisting of a plurality of contiguous overlapping trapezoidal sections, the periphery of the skirt being provided with a series of circumferentially spaced scallops forming the base edges of said sections.

80

85 In testimony whereof I affix my signature in presence of two witnesses.
